UNITED STATES PATENT OFFICE.

WILLIAM L. BLACK, OF ST. LOUIS, MISSOURI.

FIRE-PROOF BUILDING.

SPECIFICATION forming part of Letters Patent No. 278,491, dated May 29, 1883.

Application filed November 17, 1882. (No model.)

To all whom it may concern:

Be it known that I, WILLIAM L. BLACK, of St. Louis, Missouri, have made a new and useful Improvement in Means for Extinguishing Fires in Buildings, of which the following is a full, clear, and exact description, reference being had to the annexed drawings, making part of this specification, in which—

Figure 1 is a vertical section taken through a building in which the present improvement is embodied; and Figs. 2, 3, 4, details upon various scales, Fig. 2 being a vertical section, showing a portion of one of the floors of the building; Fig. 3, a view (top or bottom) showing a portion of one of the perforated sheets; and Fig. 4, a cross-section of one of the tubes, the joist, perforated sheet, and ceiling-paper also being shown.

The same letters of reference denote the same parts.

The present invention is adaptable to buildings having wooden floors and ceilings.

The invention consists, mainly, in the means for applying water to the interior of the floors and roof.

A, Fig. 1, represents a building having the improvement. Aside from the improvement, the building may be of any of the usual forms.

B B represent the walls of the building; C C' C² C³, &c., the floors, and D the roof. The floors have the usual joists, c c, and flooring, c'. The roof also consists, substantially, of the customary rafters, d d, and covering, d'.

E E represent tubes. There may be one or more of these tubes to a floor or roof, according to the extent thereof. The tubes are extended crosswise to the joists, and may be held entirely within them—that is, the joists may be perforated to receive the tubes, or the tubes may be suspended beneath the joists; but the preferable arrangement is that shown, the joists being mortised at c² to receive the tubes, as shown more distinctly in Fig. 4. The tubes are perforated at each side, as shown at e e, Figs. 1, 2, and 3, there being a set of perforations to each space c³ between the joists. At each floor, beneath the tubes E E, perforated sheets F, preferably of metal, are attached, and paper G is applied to the under side of the perforated sheet. The tubes are

connected with a water-supply—for instance, the main H, Fig. 1—and the operation of the improvement is as follows:

On opening the cocks I the water flows from the main through the pipes n n into the tubes E E, passing thence through the perforations e e into the spaces c³ between the joists. The water is supposed to flow freely from the tubes and in sufficient quantity to flood the spaces c³. The water then, after drenching the joists and flooring, trickles downward through the perforations f of the sheets F. The ceiling-paper G serves to uphold the water for a sufficient length of time to enable the interior of the floor to become thoroughly moistened, after which the water leaks downward through the paper, serving to moisten the room beneath. The water is similarly applied to the roof D. By means of cocks I any one or all of the floors can be drenched as desired. The partitions c⁴ c⁴ between the joists c c may be used to diminish the size of the spaces c³ c³ through which the water is sent—that is, in place of filling the entire space between the joists from the tubes E up to the flooring c', the water may be confined to the space beneath the partitions c⁴.

The present improvement is adaptable to other structures as well as to buildings—to steamboats and vessels, for instance.

I claim—

1. In combination with a building floor or roof having the spaces c³ c³ c³, the tube E, having the perforations e e and the perforated sheet F, substantially as described.

2. In combination with a building floor or roof having the spaces c³ c³ c³, the perforated tube E, the perforated sheet F, and the paper G, substantially as described.

3. The combination of the joists c c c, the flooring c', the perforated tube E, and the perforated sheet F, substantially as described.

4. In a building-floor, the combination of the joists c c, the partitions c⁴, and the perforated tube E, as and for the purpose described.

WM. L. BLACK.
